UNITED STATES PATENT OFFICE.

JOSEPH S. WILCOX, OF ATHOL, MASSACHUSETTS, ASSIGNOR TO THE WILCOX NOVELTY COMPANY, OF ATHOL, MASSACHUSETTS, A CORPORATION OF MASSACHUSETTS.

CELLULOID CASING FOR TIMEPIECES.

Application filed July 26, 1926. Serial No. 124,912.

This invention relates to a casing for receiving and supporting a watch or other small time piece in an upright position, so that it may serve the purposes of a small 5 table clock or desk clock.

It is the general object of my invention to provide a casing for such purposes which is simple in construction, economical to manufacture, and effective and satisfactory 10 when in use.

To the attainment of this object, I preferably provide a casing or frame having an ornamental open front member and having a rear member or back portion adapted to 15 yieldingly engage a watch or other time piece and to press the same firmly forward against the front member of the casing, but permitting convenient insertion or removal of the watch when desired.

20 A further object of the invention is to provide a casing which is adapted to receive and support watches having a considerable range of size and thickness. In the preferred form, the watch retaining rear 25 portion of the casing serves also as a brace or support for holding the casing in upright position.

My invention further relates to arrangements and combinations of parts which will 30 be hereinafter described and more particularly pointed out in the appended claims.

A preferred form of the invention is shown 35 in the drawings in which—

Fig. 1 is a front elevation of my improved 40 clock casing;

Fig. 2 is a side view thereof; and

Figs. 3 and 4 are sectional plan views, taken along the lines 3—3 and 4—4 in 45 Fig. 2.

Referring to the drawings, my improved 50 casing comprises a front member 10 and a rear member or back portion 11, both preferably formed of celluloid and permanently secured to each other by cementing the parts 55 together or in some other convenient manner.

The front portion 10 is preferably of relatively thick and rigid construction and is provided with a dial opening 12, preferably surrounded by a bevelled edge portion 13.

55 The front member 10 may be given any desired ornamental outline and the front portion thereof is commonly faced with a special or ornamental celluloid coating.

The back member 11 is preferably formed

of sheet celluloid of less thickness, so that 55 it possesses a considerable degree of resilience. The portion 11 preferably extends upward about to the center of the watch or time piece and forms in effect a substantially semi-circular pocket at the rear of the front, 60 member 10.

The middle portion 15 of the back member 11 is displaced forwardly, as indicated in Fig. 3, and is adapted to press firmly against a watch W enclosed in the casing. The portion 15 also possesses sufficient resilience to press the watch firmly against the back side of the front member 10, centering the watch in the dial opening 12 by the projecting edge 65 of the glass or watch crystal 16, as indicated 70 in Fig. 3.

The portion 15 is displaced substantially forward so that it will engage and yieldingly support a relatively thin watch, while at the same time it will yield rearwardly to 75 admit and support a relatively thick watch. The casing is thus adapted without alteration to receive and support watches of considerable variation in thickness.

Also, as the watches are usually centered 80 by the projecting glass or crystal 16, it is not necessary that the periphery of the watch fit closely in the back member 11 and a considerable variation in diameter of watch may also be permitted.

The lower portion of the back member 11 is displaced outwardly and projected downwardly, as indicated at 18, thus providing 85 for a three-point support of the casing and holding the casing in upright position.

The edges of the back member 11 may be flanged outward, as indicated in Figs. 3 and 4, to permit a more firm attachment to the front member 10.

Having described the details of construction 90 of my improved casing, it will be seen that I have provided a casing formed from two pieces of sheet celluloid, so constructed that it may be very cheaply and easily manufactured, and particularly well adapted 100 for the purposes intended.

While I have shown and described the casing as being designed for holding a watch, it will be evident that a small clock movement could be held in a similar casing 105 of suitable size.

Having described my invention and the advantages thereof, I do not wish to be lim-

ited to the details herein disclosed otherwise than as set forth in the claims, but what I claim is:—

1. A celluloid casing for supporting a time piece comprising a front member of substantial thickness and rigidity, and a relatively thin and resilient back member effective to engage the time piece and to press the same yieldingly forward against the front member, and said front member having a dial opening adapted to receive the watch crystal and to center the watch thereby in said casing.
2. A celluloid casing for supporting a time piece comprising a front member of substantial thickness and rigidity, and a back member formed of a single piece of relatively thin celluloid providing a substantially semi-circular pocket for the time piece, said back member having a resilient portion displaced forwardly and effective to exert yielding forward pressure on said time piece when supported in said casing.
3. A celluloid casing for supporting a time piece comprising a front member of substantial thickness and rigidity, and a back member formed of a single piece of celluloid providing a substantially semi-circular pocket for the time piece, said back member being formed with a resilient rear watch-engaging portion having a substan-

tial range of forward and rearward movement, whereby said casing is adapted to firmly retain watches of different thicknesses.

35

4. A celluloid casing for supporting a time piece comprising a front member and a back member forming a pocket for the time piece and having a lower open portion constricted and extended downward to form the rear member of a three-point support for said casing.

40

5. A celluloid casing for supporting a time piece comprising a front member and a back member forming a pocket for the time piece and yieldingly retaining the same therein, said back member being formed of a single piece of relatively thin resilient celluloid firmly cemented to said front member along the downwardly converging side portions of said back member.

45

6. A celluloid casing for supporting a time piece comprising a front casing member having an opening through which the time piece is visible, and a relatively thin resilient back casing member effective to engage the time piece and to press the same yieldingly forward against the periphery of said opening.

50

In testimony whereof I have hereunto affixed my signature.

JOSEPH S. WILCOX.
